Primary Examiner — Lauren R Calve*(74) Attorney, Agent, or Firm* — JoAnn M. Seaton;
Griffiths & Seaton PLLC(57) **CLAIM**

The ornamental design for a garment hanger, as shown and described.

DESCRIPTION

FIG. 1 is a front, perspective view of a garment hanger showing our new design;

FIG. 2 is a front view thereof, wherein the rear surfaces thereof are unclaimed such that a rear view is omitted;

FIG. 3 is a right side view thereof;

FIG. 4 is a left side view thereof;

FIG. 5 is a top view thereof; and,

FIG. 6 is a bottom view thereof.

In the drawings, the broken lines depict unclaimed subject matter only and form no part of the claimed design. The features shown in long dash-short dash bolded broken lines indicate the bounds of the claimed design and otherwise form no part of the claimed design.
